(57) **CLAIM**

I claim the ornamental design for an electronic oven, as shown and described.

DESCRIPTION

FIG. 1 is a top front perspective view of an electronic oven showing our new design;

FIG. 2 is a front elevational view thereof;

FIG. 3 is a rear elevational view thereof;

FIG. 4 is a left side elevational view thereof, the right side being a mirror image; and,

FIG. 5 is a top plan view thereof.
